UNITED STATES PATENT OFFICE.

HARRY T. HASKINS, OF DENVER, COLORADO.

CONTACT BRUSH FOR TIMERS.

1,425,200.

Specification of Letters Patent. Patented Aug. 8, 1922.

Application filed March 22, 1921. Serial No. 454,434.

To all whom it may concern:

Be it known that I, HARRY T. HASKINS, a citizen of the United States of America, residing at the city and county of Denver 5 and State of Colorado, have invented a new and useful Contact Brush for Timers, of which the following is a specification.

This invention relates to improvements in distributor brushes for commutator timer 10 rings for internal combustion engines, and is designed as an improvement over a similar device for which an application for a patent in the United States was filed on August 27, 1920, bearing Serial Number 15 406407.

The object of the present invention is to provide a resilient spring distributor brush which makes a positive sliding contact with all contact points of the timer, whereby a 20 strong steady spark is assured.

Further, to provide a metal sliding contact distributor brush which is pivotally attached to a support secured on the cam shaft of an internal combustion engine, said 25 brush being held in positive engagement with the timer ring by a spring mounted on said support, and which is so arranged that should the brush break, said spring would immediately engage the timer and act as a 30 brush until its replacement by a new brush.

These objects are accomplished by the mechanism illustrated in the accompanying drawings in which:

Figure 1 is a side view of an automobile 35 engine, illustrating the application of my invention.

Fig. 2 is a front view showing the improved resilient brush connected to the cam shaft of an engine and in engagement with 40 the commutator ring, the commutator casing being in section.

Fig. 3 is a section view on the line 3—3 of Figure 2, the distributor brush being 45 shown in full lines.

Fig. 4 is a perspective view of the distributor brush, its support, and its tension spring.

Fig. 5 is a perspective view of the brush proper, detached, and looking at the opposite side to that shown in Figure 4.

Fig. 6 is a plan view of the blank from which the brush support is formed. And

Fig. 7 is a perspective view of the front 55 end of the engine casing with the commutator thereon.

Referring to the accompanying drawings:

The numeral 1 designates an automobile engine; 2, the casing which encloses the valve turning gears of the engine; 3, the commutator case; 4, the cam shaft; 5, the 60 crank shaft; 6, the small timing gear which is secured to the crank shaft; 7, the large timing gear which is secured to the cam shaft, and 8, the fiber timing ring which is secured to the inner wall of the commuta- 65 tor casing.

The above named parts are in general use in automobile engines and form no part of the present invention and are mentioned only to show the co-operative relation between them and the present invention which relates solely to the spark timing distributor brush, which by reason of its construction and arrangement assures a positive contact between the said brush and the contact 70 points of the timer ring, thereby giving a 75 stronger and steadier spark than can be produced by the timers in general use at the present time.

The distributor brush forming the present 80 invention comprises the brush proper, 9, a support, 10, for said brush, and a tension spring 11, for holding the brush in continuous contact with the timer ring, which parts are constructed and arranged in the follow- 85 ing manner:

The support 10 is made from a metal strip of the shape shown in Figure 6. Approximately one-half of this strip is of greater width than the remaining portion, the narrower portion being about two-thirds of the width of the wider portion. The wider portion of the strip is rolled upon itself to form a hub 12, which is adapted to fit tightly upon the outer end of the cam shaft 4, which projects into the commutator casing 3, and which is formed with a shoulder 13, against which the inner edge of the hub 12 abuts. A recess 14 is cut into the hub from its outer edge, and this recess fits over a pin 15, which 90 is driven into a hole in the end portion of the cam shaft, whereby the support is held against turning on the said shaft. A second shoulder 16 is formed on the shaft, slightly 95 beyond where the pin enters, and the reduced portion of the shaft beyond the shoulder 16 is threaded, as shown. A cupped washer 17 is slipped upon the threaded end of the shaft and against the shoulder 16, the rim portion of said washer surrounding the 100 outer end portions of the hub 12, and thus 105 serving to hold the pin 15 in its hole, as will

110

be understood by reference to Figure 3, and a nut 18 is screwed upon the end of the shaft and against the washer, thereby holding the washer in place on the shaft. The narrow portion of the support is curved outward as shown in Figures 2 and 4, and its free end portion is bent upon itself to form a roll 19, and a slot 20 is formed in this narrow part of the support, which extends from the roll 19 about to where the wide portion of the support begins.

The brush 9 is made of the best quality of spring steel, one end portion of which is wider than the opposite end portion, and this wide portion is rounded and is bent into semicircular form, as shown at 21. The curved end 21 forms the contact end of the brush and it is therefore case hardened to give it the necessary wearing quality.

The opposite end of the brush is rolled upon itself to form a sleeve 22, which is of a size to fit closely over the roll 19, and the free straight end of this sleeve is formed with a projecting tongue 23, as clearly shown in Figure 5. In slipping the sleeve 22 over the roll 19, the outer or contact end of the brush is swung down to rest against the hub 12 of the support so that the tongue 23 will not contact with the edge of the support and when the sleeve is in place on the roll, the brush is swung up to the position shown in Figure 4, and in this position the tongue 23 projects through the slot 20 and prevents the brush from being accidentally disconnected from the support. Two transverse slots 24, are also cut in the strip 10 near the free end of the wide portion from which the hub 12 is formed, and one end of the spring 11 is passed through these two holes in the manner shown in Figure 2, so that the short portion of the spring, between the two holes, lies against the inner face of the hub, and the adjacent end of the spring is bent down against the outside of the hub to prevent the spring from being accidentally detached from the hub. The free portion of the spring is then bent around, as shown, and its free end is passed through the slot 20, and permitted to bear against the under side of the brush, which is thus forced outward until the edge of the sleeve 22, on each side of the tongue 23, engages the support, by which further outward movement of the brush is prevented. The assembled support, brush and spring, now appear as shown in Figure 4, and is ready to be secured upon the end of the cam shaft.

In practice, the common form of commutator casing 3 and timer ring 8 are employed in connection with the improved brush, the said casing 3 being adapted to be turned upon its axis on the engine casing in the usual manner, to advance or retard the spark, and being held in engagement

with the engine casing by a spring 25, one end of which is bolted to the engine casing, while the opposite end thereof bears resiliently against the end of the casing 3.

In order to replace one of the common form of roller contacts with one of the improved spring distributor brushes, or to replace a worn or broken brush with a new one, the free end of the spring 25 is lifted from the casing 3, permitting the same to be withdrawn from its bearing in the end of the engine casing, and thus enabling the old roller or brush, as the case may be, to be renewed. The hub 12 of the support is then slipped upon the end of the cam shaft, the brush being pressed down against the tension of the spring 11, to enable it to pass within the timer ring 8, the pin 15 is passed through the recess 14 in the hub and into its hole in the cam shaft, the cupped washer 17 is then slipped over the end of the hub to hold the pin in place, and the nut 18 is screwed on the end of the shaft and against the cupped washer, thus securely holding the brush and its parts upon the shaft. The spring 11 being under tension exerts a continuous outward pressure on the brush which holds it positively against the ring 8, and as the cam shaft rotates, the brush slides smoothly over the contacts 26, in the timer ring, which are connected by wires with the coil box in the usual manner. As the spring brush has a sliding engagement with the contacts 26 the faces of the said contacts wear off smoothly and evenly, and never in 100 ruts or hollows, as is the case where the roller brush is employed, and for this reason the spring brush is not subject to a jumping or bouncing action, with the consequent imperfect engagement of brush and contact resulting necessarily in imperfect sparking.

The improved spring brush produces such a strong and steady flow of current at the spark plugs that if they are kept clean it is impossible for them to miss sparking, and thus with the employment of the improved spring brush, a car will run more evenly and with a greater mileage from a given quantity of fuel than with the common type of roller brush.

While I have illustrated the preferred construction and arrangement of the current distributor brush, I do not wish to be limited to the precise arrangement, as various changes might be made without departing from the spirit and scope of the invention.

Having described my invention, what I claim as new and desire to secure by Letters Patent, is:

1. A current distributor brush of the character described, comprising a metal strip bent to form a hub having an arm projecting therefrom, the outer end of which is bent upon itself to form a roll, a spring brush, one end of which is bent to form a

sleeve which is pivotally mounted on said roll, means for preventing accidental disconnection of the brush from the roll, and a spring secured at one end to said hub, its 5 opposite end exerting an outward pressure against the under side of said brush.

2. A current distributor brush of the character described, comprising a metal strip, one portion of which is narrower than the other and formed with a slot, the wider portion being bent upon itself to form a hub, while the narrower part projects therefrom, its free end being formed into a roll; a spring brush, one end of which is formed 10 into a sleeve which is pivotally mounted on said roll, a tongue on said sleeve which extends through said slot and prevents accidental disconnection of the brush from the roll, and a spring, one end of which is secured to said hub, its opposite end portion being bent around and passed through said 15 slot in position to exert an outward pressure against the under side of said brush.

3. A current distributor brush of the character described, comprising a metal strip, one portion of which is narrower than the other and formed with a longitudinal slot, the free end of said narrow portion being formed in a roll, the wider portion of said 20 strip being bent to form a band or hub and having a recess in one edge thereof; a spring steel brush, one end of which terminates in a curve, its opposite end being bent upon itself to form a sleeve which is pivotally 25 mounted on said roll, an integral tongue on the edge of said sleeve which projects through said slot and prevents accidental disconnection of the sleeve from the roll, and a spring, one end of which is secured in 30 apertures in said hub, its opposite end portion being bent around and passed through said slot in position to exert an outward pressure against the under side of said brush.

4. A current distributor brush of the character described, comprising a resilient support consisting of a band or hub having a recess in one edge thereof, and an outwardly 45

curved arm provided with a longitudinal slot, the end portion of said arm being bent upon itself to form a roll, a steel spring 50 brush having a curved contact end, its opposite end being in the form of a sleeve which is pivotally mounted on said roll, and having an integral tongue which extends through said slot and prevents accidental 55 disengagement of the sleeve from the roll, the tongue being freed from the slot when the contact end of the brush is swung inward against the said hub, the edge of said sleeve on each side of said tongue being 60 adapted to engage the under side of said arm to prevent excessive outward movement of the brush, and a spring, one end of which is secured in apertures in said hub, its opposite end portion being bent around and 65 passed through said slot in position to exert an outward pressure against the under side of the brush.

5. The combination with the cam shaft of an internal combustion engine, and a timer 70 ring concentric with the axis of said shaft, of a spring strip, one portion of which is in the form of an arm, the free end of which is formed in a roll, the other portion being formed into a hub which fits upon said shaft, and means for securing said hub against rotation on said shaft, a brush, one 75 end of which is formed into a sleeve which is pivotally mounted on the rolled end of said arm, said arm having a slot therein, and a spring, one end of which is passed through apertures in said hub, and between the hub 80 and the shaft, its opposite end portion being bent around and passed through the slot in said arm in position to press the free end of said brush into engagement with the inner face of said timer ring.

In testimony whereof I affix my signature in presence of two witnesses.

HARRY T. HASKINS.
